UNITED STATES PATENT OFFICE.

CLARENCE E. HAWKE, OF METUCHEN, NEW JERSEY, ASSIGNOR TO THE CARBORUNDUM COMPANY, OF NIAGARA FALLS, NEW YORK, A CORPORATION OF PENNSYLVANIA.

COMBUSTION CHAMBER.

Application filed May 12, 1925. Serial No. 29,654.

The present invention relates to combustion chambers, and more particularly to radiating combustion chambers of the double pass type disclosed in the patent to Clarence E. Hawke and Boyd M. Johnson, No. 1,542,552, granted June 16, 1925.

This type of combustion chamber, as shown in said co-pending application, is usually constructed with an internal horizontal partition which separates the two passes except at the rear end of the chamber where they communicate with each other. In using this type of combustion chamber it has been found that in certain cases where the combustion rate was very high, as when burning oil, there was a tendency to overheat this partition member which had no chance to radiate its heat, the result being that it gave way of its own weight and rendered the furnace inoperative. When burning powdered coal in this type of combustion chamber, there is also the danger of overheating the ash to the point where it fuses and this also destroys the partition.

By the present invention I propose to overcome these difficulties by providing a construction in which it is possible for all surfaces of the double pass chamber to radiate heat so that in burning pulverized coal or other materials of an erosive nature, the surfaces of the refractories of which the combustion chamber is composed will all be cooled to a point where the slags will not react with the silicon carbide or other refractory material out of which the walls of the combustion chamber are constructed. With this construction the walls of the combustion chamber are also more uniformly heated than in the type of combustion chamber having the internal partition and a larger amount of radiating surface is provided.

In the accompanying drawings:

Figure 1 is a transverse sectional view through a furnace adapted for the heat treatment of ceramic ware and similar articles and having a preferred form of combustion chamber constructed in accordance with my invention installed therein;

Figure 2 is a section on the line II-II of Figure 1;

Figure 3 is a transverse sectional view of the combustion chamber shown in Figure 1 on a slightly larger scale;

Figure 4 is a side elevation partly broken away of a portion of the combustion chamber;

Figure 5 is a perspective view of a modified form of combustion chamber embodying my invention;

Figure 6 is a perspective view of one of the hollow tiles used for spacing the top of the bottom pass from the bottom of the top pass in the construction shown in Figure 5; and

Figure 7 is a perspective view of another modification of my invention.

Referring to the construction shown in Figures 1 to 4 inclusive, 2 designates a heat treating furnace having a heating chamber 3 within which and arranged adjacent to the opposite sides thereof are two radiating combustion chambers 4 embodying my invention. Each combustion chamber is divided into an upper pass 5 and a lower pass 6 by a horizontal X-shaped partition 7 extending from the front end of the chamber nearly to the rear end thereof. The upper pass 5 has a burner opening 8 in the front end thereof into which projects an oil burner 9 supplied with oil through a pipe 10. Secondary air is supplied to the burner opening 8 through a pipe 11. The forward end of the lower pass 6 of each combustion chamber communicates with a flue 12 beneath the floor of the heating chamber 3.

By reference to Figures 3 and 4 it will be seen that the four inclined walls 13, 14, 15 and 16 of the X-shaped partition are reinforced at intervals throughout the length of the partition by vertical webs 17. The outer surfaces of the X-shaped partition are exposed to the outside air so that the walls of the X-shaped partition are adapted to radiate heat as freely as the remaining portions of the walls of the upper and lower passes and consequently the walls of the X-shaped partition will not be exposed to substantially greater temperature conditions than the remaining portions of the walls of the passes. It will be appreciated also that this construction greatly increases the total amount of radiating surface of the combustion chamber as compared with the type of construction in which the usual internal horizontal partition is employed.

In the modified construction shown in Figure 5 the upper and lower passes 18 and 19 of the combustion chamber are separated

by a ventilated horizontal partition 20 formed of hollow tiles 21. These hollow tiles form the top wall of the lower pass and bottom wall of the upper pass. This ventilated partition permits the free circulation of air through the same and is adapted to radiate heat freely.

In the modified construction shown in Figure 7 the upper pass 22 of the combustion chamber has its bottom wall separated from the top wall of the lower pass 23 of the chamber by ordinary bricks 24 or other suitable shapes spaced apart to permit circulation of air between said lower and upper walls and to permit said walls to radiate heat freely. It will be seen that in this construction the two passes of the combustion chamber may be built up of individual sections 25. The construction really amounts to a single pass combustion chamber set on top of another single pass combustion chamber with means for connecting the two passes at the rear end thereof and with means for spacing the two passes from each other.

While I have shown and described certain embodiments of my invention, it will be understood that the invention is not limited to its illustrated embodiments, but that it may be otherwise embodied within the scope of the appended claims without departing from the spirit of the invention.

I claim:

1. A unitary combustion chamber structure having two substantially parallel passes extending longitudinally thereof and communicating with each other at one end of the structure, said passes being adapted to communicate at the opposite end of the structure, one with means for supplying combustible material and the other with an outlet for the products of combustion, the walls separating said passes from each other having sufficient exposed surfaces to enable said walls to radiate heat freely, substantially as described.

2. A unitary combustion chamber structure having two superposed passes extending longitudinally thereof and separated by walls having sufficient exposed surfaces to enable said walls to radiate heat freely, said passes communicating with each other at one end of the structure and being adapted to communicate at the opposite end of the structure, one with means for supply-

ing combustible material and the other with an outlet for the products of combustion, substantially as described.

3. A unitary combustion chamber structure having two superposed passes extending longitudinally thereof and communicating with each other at one end of the structure, said passes being adapted to communicate at the opposite end of the structure, one with means for supplying combustible material and the other with an outlet for the products of combustion, the bottom wall of the upper pass and the top wall of the lower pass having spaced supports interposed therebetween and said walls having sufficient exposed surfaces to enable said walls to radiate heat freely, substantially as described.

4. A unitary combustion chamber structure having upper and lower passes communicating at one end and separated by an intervening wall structure, said intervening wall structure having heat radiating pockets therein.

5. A unitary combustion chamber structure having forward and return passes which communicate with each other at one end of the structure, a fuel burner opening into one end of one of the passes, said passes being separated by a partition having transversely arranged heat radiating cavities therein.

6. A unitary combustion chamber structure having forward and return passes and formed of a refractory material having a high coefficient thermal conductivity, the two passes being separated by a common partition having heat radiating pockets therein.

7. A unitary combustion chamber structure formed of a good heat conducting refractory material, said structure having forward and return passes therein, said passes being separated by a common wall structure having heat radiating cavities passing therethrough.

8. A unitary combustion chamber structure having forward and return passes therein separated by a heat radiating partition, said partition having exposed pockets therein by means of which the radiating surface thereof is effectively increased.

In testimony whereof I have hereunto set my hand.

CLARENCE E. HAWKE.
